UNITED STATES PATENT OFFICE.

ARTHUR E. SMITH, OF LOS ANGELES, CALIFORNIA.

AMPUL.

Application filed March 25, 1927, Serial No. 178,388. Renewed May 10, 1929.

This invention relates to a medicinal container or ampul.

The main object of this invention is to provide an improved drug containing ampul wherein the drug in the ampul is hermetically sealed therein.

Another object of the invention is to provide a drug containing ampul having an improved form of stopper therein for ejecting the contents of the ampul.

Another object of the invention is to provide an ampul having novel means thereon for coacting with a syringe to form a fluid tight seal between the syringe and the ampul.

A further object of the invention is to provide a novel method of placing a fluid in an ampul.

Other objects of the invention will be apparent from the following description taken in connection with the accompanying drawing wherein:

Fig. 1 is a central longitudinal section through my improved medicinal container or ampul.

Fig. 2 is a side elevation on a reduced scale of the tube from which a single ampul is made.

Fig. 3 illustrates the first step in the forming of an ampul.

Fig. 4 illustrates the second step.

Fig. 5 illustrates the third step.

Fig. 6 is a fragmentary section showing the fourth step or the manner in which the fluid is placed in the ampul.

Fig. 7 is a side elevation of a completed ampul, and

Fig. 8 is a side elevation of an ampul showing it prepared for use in a syringe.

Referring to the drawings by reference characters I have indicated my improved ampul generally at 10. This ampul is adapted for use in a hypodermic syringe. The ampul may be of any desired size and is preferably of a size to hold the amount of drug necessary for one injection.

The ampul 10 comprises an elongated body portion 11 terminating at one end in a reduced tapered neck 12 which terminates in a breakable tip 13. The other end of the body portion 11 merges into a constricted throat 14 which terminates in a breakable tip 15. The tips 13 and 15 may be rendered readily separable from the ampul by scoring, notching, etching, or otherwise weakening them as indicated at 16 and 17.

Within the ampul body 11 and adjacent the throat 14 I provide a stopper 18 which is preferably made of a good grade of rubber and fits the inner side walls of the ampul body rather tightly, enabling it to act as a piston to expel the contents of the ampul through the tapered end 12 after the tip 13 has been broken therefrom.

The stopper 18 is preferably provided on its face adjacent the throat 14, as shown in the drawing, with a washer 19 having a tapered hub 20 thereon which is adapted to fit in a recess 21 of the stopper. The recess 21 has undercut ends 21'. The hub 20 is provided with a tapered aperture 22 extending therethrough. The hub 20 has a rolled terminal edge 20' which fits in the undercut portion 21' to unite the parts.

The tapered aperture 22 is adapted to receive the tapered end of a plunger rod of a hypodermic syringe with which the ampul may be used. The other face of the stopper 18 may be concave as at 23 so that when the stopper is acting as a piston to eject the contents of the ampul the peripheral edges of the concavity will be forced into tight engagement with the inner walls of the body portion, thus preventing any of the fluid from leaking past the stopper as it is moved.

For forming a fluid tight seal between the ampul 10 and a syringe with which the ampul is used I provide on the tapered neck 12 just above the fracture 16, a resilient collar 24 which is preferably made of rubber.

The foregoing ampul is preferably made of a good grade of glass and is preferably formed from a length of glass tubing 25 as shown in Fig. 1. This tubing is first heated and drawn down to form the constricted throat 14, the end of which is left open as at 26 (see Fig. 3), then the stopper 18 is inserted into the tube 25 through the open end 27 and moved in the tube to a position as close to the constricted throat 14 as the size of the metal stopper washer 19 will allow (see Fig. 4). The open end 27 of the tube is then heated and drawn down to form the tapered neck 12 and the closed tip 13, the full body portion of the tube 25 forming the body 11 of the completed ampul. After the tapered end 12 has been formed and closed by the tip 13 the ampul is ready to be filled with a drug or other fluid.

To fill the ampul 10 I insert through the stopper 18 and into the interior of the ampul

body 11 a pair of hollow needles 28 and 29 as shown in Fig. 6. The needle 28 is shown as having attached thereto a flexible hose 30 which is adapted to communicate with a 5 source of drug supply (not shown). As the drug enters the ampul body 11 through the needle 28 the air it displaces will pass out through the other hollow needle 29.

I have described one manner in which the 10 drug may be placed in the ampul body 11 and the air is removed therefrom by the needles 28 and 29 but various other methods may be employed and I do not wish to be held to any single method of accomplishing this. Upon 15 the withdrawal of the needles 28 and 29 the elasticity of the stopper 18 will close the minute apertures made by the needles and thus the fluid will not leak out through the needle punctures.

20 After the ampul has been filled with the desired drug the open end 26 is heated and drawn down to form the closed tip 15 and then it may be etched, scored, notched, or otherwise weakened at 16 and 17. The collar 24 is 25 then placed on the tapered neck 12 and the ampul is complete and ready for use (see Fig. 7).

To prepare the ampul 10 for use in a 30 syringe the tip 13 is broken off at 16 and the tip 15 is broken off at 17 as clearly shown in Fig. 8. The ampul is then placed in the syringe, the plunger of the syringe engages the stopper 18 and as the syringe plunger is moved towards the tapered end 12 the stopper 35 18 is caused to act as a piston to expel the contents of the ampul out through the tapered neck 12.

From the foregoing description it will be 40 apparent that I have provided an improved form of container or ampul having therein a movable fluid restricting stopper, and wherein means is provided for filling the ampul after the stopper is in position, and wherein in the finished ampul the fluid contained 45 in the ampul and the stopper are hermetically sealed within the ampul.

What I claim is:

1. An ampul comprising a body portion having a stopper therein, said stopper having 50 a recess therein and having a washer on one face, said washer including a hub portion adapted to be positioned in said recess in said stopper, said hub having therethrough an aperture and said aperture being tapered.

55 2. An ampul adapted for use in a syringe having means for engaging the ampul at both ends comprising a body portion constricted at one end to form a throat and a closed tip, means adjacent the narrow portion 60 of said constricted throat to weaken it and make the tip bodily removable from said ampul by breaking, the opposite end of said body portion being constricted to form a tapered neck portion, said neck terminating 65 in a closed tip and means adjacent said neck

for weakening it to make the tip readily removable by breaking, a resilient collar surrounding a portion of said tapered neck, said collar being positioned on said neck adjacent to said weakening means, a stopper in said body portion adjacent said constricted throat, said stopper having engagement with the inner surface of said body portion to form a fluid tight seal between said ampul and said stopper, said constricted throat and said 75 tapered neck being adapted to be engaged by the syringe to hold the ampul therein.

3. An ampul comprising a body portion having a stopper therein, said body portion being constricted at one end to form a tapered 80 neck portion, said neck terminating in a tip, a resilient collar arranged on said tapered neck, said stopper having engagement with the inner surface of said body portion to form a seal between said ampul and said stopper, said stopper being adapted to be moved within said body portion to act as a piston to expel the contents of said ampul out through said previously mentioned neck after said tip 85 has been removed from said ampul, said stopper having a recess therein and having a washer on one face, said washer including a hub portion adapted to be positioned in said recess in said stopper.

4. An ampul comprising a body portion 90 constricted at one end to form a throat and a closed tip, means adjacent the narrow portion of said constricted throat to weaken it and make the tip readily removable from said ampul by breaking, the opposite end of said body portion being constricted to form a 95 tapered neck portion, said neck terminating in a closed tip and means adjacent said neck for weakening it to make the tip readily removable by breaking, a resilient collar surrounding 100 a portion of said tapered neck, said collar being positioned on said neck between said weakening means and said neck, a stopper in said body portion adjacent said constricted throat, said stopper having tight engagement with the inner surface of said body portion to form a fluid tight seal between said

105 ampul and said stopper, said stopper being adapted to be forcibly moved within said body portion to act as a piston to expel the contents of said ampul out through said neck after both of said previously mentioned closed tips have been removed from said ampul, said stopper having a recess therein and having a 110 washer on its face adjacent the constricted throat, said washer including a hub portion adapted to be positioned in said recess in said stopper, said hub having an aperture 115 therethrough and said aperture being tapered, said stopper having a concave recess in its opposite face whereby when said stopper is actuated as a piston to expel the contents of said ampul the outer peripheral edges of said face will be forced by the pressure into 120 tight engagement with the interior of said

125 130 ampul.

body portion, thereby forming a fluid tight joint between said stopper and said body portion.

5. An ampul adapted for use in a syringe having means for engaging the ampul at both ends, said ampul comprising a hollow body constricted at one end to form a throat to be engaged by one portion of the syringe, a stopper in said body portion adjacent to said constricted portion, the opposite end of said body portion being tapered and adapted to be engaged by another portion of the syringe, both ends of the ampul being provided with closed tips having weakened portions.
- 10 6. An ampul adapted for use in a syringe having means for engaging the ampul at both ends, said ampul comprising a hollow body constricted at the rear end to form a throat to be engaged by one portion of the syringe,

a movable stopper in said body portion adjacent to said constricted portion, the front end of said body portion being tapered and adapted to be engaged by another portion of the syringe, said front end of the ampul being provided with a closed tip having weakened portions.

7. For use in a syringe having a plunger, an ampul, a stopper movable in said ampul, a washer associated with said stopper, said washer including a plane portion engaging one face of said stopper and another portion embedded in said stopper, said washer having a recess therein, said recess being adapted to receive the syringe plunger.

In testimony whereof, I hereunto affix my signature.

ARTHUR E. SMITH.
